VALVE FOR ROCK DRILLS

Filed April 9, 1927

FIG.-1.

FIG.-2.

INVENTOR.
Earl B. Lear.
BY *Robert B. Dyer*
HIS ATTORNEY.

UNITED STATES PATENT OFFICE.

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY.

VALVE FOR ROCK DRILLS.

Application filed April 9, 1927. Serial No. 182,328.

This invention relates to rock drills, but more particularly to a distributing valve for fluid actuated rock drills of the hammer type.

5 The objects of the invention are to obtain a durable valve of light weight, to effect a rapid distribution of pressure fluid to the cylinder, and to hold the valve firmly in its extreme positions during the admission of 10 pressure fluid to the cylinder.

Other objects will be in part obvious and in part pointed out hereinafter.

In the drawings illustrating an embodiment of the invention,

15 Figure 1 is a longitudinal sectional elevation of a portion of a rock drill showing the valve in position to admit pressure fluid to the rearward end of the cylinder, and

20 Figure 2 is a view similar to Figure 1 showing the valve in its other limiting position.

Referring to the drawings, the invention is shown embodied in a rock drill having a cylinder A closed at its front end by a bushing B and at its rearward end by a back head C. The cylinder A is provided with a hammer piston D which controls a free exhaust port E in the cylinder and has a forwardly extending reduced shank F slidable 30 in the bushing B.

35 Formed on the cylinder A is a valve chest G having an annular bore H which extends from the rearward end of the chest to a point near the front end thereof, thus forming an end wall J in the chest G.

40 At the opening of the bore H is formed an annular recess K to receive a flange L of a bushing O having in this instance a passage P which communicates with a passage Q in the back head C. Preferably a throttle valve R of any suitable type is interposed in the passage Q to control communication between the passage P and a source of pressure fluid supply (not shown).

45 In the front end of the bore H is disposed a bushing S which abuts the wall J and has a threaded extension T projecting through the wall J to receive a nut U whereby the bushing S is secured firmly in position. The bushings O and S are bored to form a 50 valve chamber V and are spaced to form an

enlarged portion X in the valve chamber V.

Pressure fluid for actuating the piston D is conveyed to the cylinder through inlet passages Y and Z leading from the rearward 55 and front ends respectively of the valve chamber V to the corresponding ends of the cylinder A.

Disposed in the valve chamber V is a distributing valve b having in this instance a bore c therethrough for conveying pressure fluid from the passage P to the inlet passage Z. The rearward and front ends d and e respectively of the valve are preferably so formed as to enable them to lie flush against the adjacent ends f and g of the bushings O and S. The ends d and e when out of contact with their respective faces which they are intended to abut serve as holding faces against which pressure fluid may act 70 for holding the valve in their extreme positions. For instance, with the valve in the position illustrated in Figure 1, the end face d is exposed to live pressure fluid flowing into the inlet passage Y and the face e 75 is thus held firmly against the face g of the bushing S.

Intermediate the ends of the valve is formed an enlarged flange h which reciprocates in the enlarged portion X of the valve chamber and thus divides the said enlarged portion into forward and rearward pressure chambers j and k into which pressure fluid is constantly conveyed from the interior of the valve by leak ports o and p to act against 85 forward and rearward surfaces q and r respectively of the flange h. The end surfaces q and r of the flange h in this instance constitute both actuating and holding faces and are constantly subjected to pressure fluid 90 under varying pressures.

In order to provide a controlled escape for the pressure fluid admitted into the pressure chambers j and k, said pressure chambers are provided with exhaust passages s and t 95 which open into the cylinder A preferably at points near the free exhaust port E and are controlled by the piston D.

The operation of the device is as follows: With the valve b in the position illustrated 100 in Figure 1, pressure fluid flowing through the inlet passage Y to the rearward end of

the cylinder will actuate the piston D forwardly. As will be observed, at the beginning of the forward stroke of the piston D, the passage *t* will be covered thereby so that 5 the pressure fluid flowing through the leak port *p* will be entrapped in the pressure chamber *k* and, acting against the surface *r* of the flange *h*, will hold the forward end *e* of the valve firmly against the end *g* of the 10 valve chamber, thus sealing the front end of the valve. Any slight admission of pressure fluid, however, which may leak past the cooperating surfaces of the valve and the valve chamber may pass directly to the 15 atmosphere through the free exhaust *E*, as may also the pressure fluid that enters the pressure chamber *j* while the valve is in this position. An additional holding effect is obtained while the valve is in its forward 20 position by the pressure fluid acting against the end *d* during its passage from the passage *P* into the rearward end of the cylinder.

Immediately prior to the opening of the 25 free exhaust port *E* by the piston D, the rearward exhaust passage *t* will be uncovered by the piston so that the pressure fluid in the pressure chamber *k* may escape through these channels, along with the pressure fluid in the rearward end of the cylinder, to atmosphere.

Shortly before communication between the atmosphere and the pressure chamber *k* is established, the front exhaust passage *s* 30 will be covered by the piston and the pressure fluid flowing into the pressure chamber *j* will then be entrapped therein and, acting against the surface *q* of the valve flange *h*, will move the valve rearwardly to the position 35 illustrated in Figure 2 at about the time the piston D delivers its blow to the working implement (not shown). By moving the valve rearwardly, direct communication between the interior of the valve and the front end of the cylinder will have been 40 established and the pressure fluid will then flow into the front end of the cylinder to drive the piston D rearwardly.

As will be apparent, the pressure fluid in 45 the pressure chamber *j* will remain entrapped therein and, assisted by the pressure acting against the front end *e* of the valve, will hold the valve in its rearwardmost position until communication between the passage *s* and the free exhaust port *E* is again 50 established by the piston, whereupon the pressure fluid in the pressure chamber *j*, together with the pressure fluid in the front end of the cylinder will be exhausted to the

atmosphere, thus completing the cycle of 60 operations.

I claim:

1. In a fluid actuated rock drill, the combination of a cylinder and piston, a valve chest having a valve chamber, a distributing valve in the valve chamber having a bore for conveying pressure fluid therethrough, the ends of said valve cooperating with the ends of the valve chamber for controlling the admission of pressure fluid to the cylinder, a flange on the valve having actuating and holding surfaces, ports constantly conveying pressure fluid into the valve chamber to act against the surfaces, and passages for exhausting such pressure fluid into the cylinder after the valve has been actuated. 75

2. In a fluid actuated rock drill, the combination of a cylinder and piston, a valve chest having a valve chamber, a distributing valve in the valve chamber having a bore for conveying pressure fluid therethrough, the ends of said valve abutting the ends of the valve chamber to effect a reduction in pressure on one end of the valve while pressure fluid is flowing over the other end, a flange on the valve having opposed actuating and holding surfaces, ports in the valve conveying pressure fluid into the valve chamber to act against the surfaces for throwing the valve and for holding it in thrown position, and passages in the valve chest for exhausting such pressure fluid from the valve chamber into the cylinder, said passages being controlled by the piston. 85

3. In a fluid actuated rock drill, the combination of a cylinder and piston, a valve chest having a valve chamber with an intermediate enlarged portion, a valve in the valve chamber having a bore for conveying pressure fluid therethrough, the ends of the valve constituting holding surfaces and cooperating with the ends of the valve chamber to effect a reduction of pressure on one end while the other end is exposed to pressure fluid, a central flange on the valve dividing the enlarged portion of the valve chamber into pressure chambers, ports in the valve constantly conveying pressure fluid into the pressure chambers to actuate the valve, exhaust passages leading from the pressure chambers to the cylinder, and a free exhaust port in the cylinder, said exhaust passages and exhaust ports being controlled by the piston. 100

In testimony whereof I have signed this specification.

EARL B. LEAR.
